UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FRAME.

1,113,979.

Specification of Letters Patent.

Patented Oct. 20, 1914.

Application filed June 5, 1912. Serial No. 701,735.

To all whom it may concern:

Be it known that I, FRANZ A. FULLER, a citizen of the United States, residing in the city of Newark, in the county of Essex and State of New Jersey, have invented certain new and useful Improvements in Bag-Frames, of which the following is a full, clear, and exact description, such as will enable others skilled in the art to which it pertains to make, construct, and use the same, reference being had to the accompanying drawings, and to letters of reference marked thereon, forming a part of this specification.

15 My invention relates to improvements in bag frames for bags or purses, and especially for traveling, chatelaines and similar bags, and has for its object, the production of a neat, inexpensive and efficient bag frame which is extremely durable, and is not liable to breakage when unduly strained or used continually, and to this end, it consists in the detail construction and arrangement of the parts, as hereinafter particularly described and pointed out in the claims.

In describing this invention, reference is had to the accompanying drawings forming a part of this specification, in which like letters of reference indicate corresponding parts in all of the views.

Figure 1 represents a vertical sectional view of my improved bag frame in its closed position. Fig. 2 represents a plan view of my improved bag frame showing the intermediate frame member in an angular position. Fig. 3 represents a sectional end elevation taken on lines $x-x$ of Fig. 2, looking in the direction indicated by the arrow; and Fig. 4 represents an enlarged sectional fragmentary view of one of the outside frame members.

In the drawings, a and b indicate the usual outside pair of frame members and c the usual intermediate frame member, which are pivotally secured at their lower end portions by means of suitable pins or rivets d , or they may be pivotally connected with each other in any other well known manner. The outside U-shaped frame sections a and b , each comprising a main body portion and end members extending therefrom formed from an unbroken flat piece of sheet metal, and so formed by means of suitable punches and dies, that a continuous integral upwardly and outwardly extending flange e

extending around the inner edge of said body portion and the end members is formed, see Fig. 4 of the drawings.

The continuous flanges e of the outside frame members a and b , when the frame is in a closed position, as illustrated in Fig. 1 of the drawings, entirely cover the intermediate frame member c , said intermediate frame member c filling in the space between the two outer frame members, which when so assembled, the continuous flanges e produce a raised surface extending entirely around the frame sections, thereby imparting to said outside frame members considerable stability and rigidity.

70 The different frame members a , b and c are preferably channeled-shaped as shown and each formed from an unbroken flat piece of sheet metal. In the construction of the outside frame members a and b , the flat piece of metal is so formed as to provide the continuous flange e extending around the inner edge of said frame members by lapping or folding the metal together to provide rigidity and stability to the frame members. The shape or configuration of the flange e can be made to conform to any desired shape of the intermediate frame member c .

75 Experience has demonstrated that the organization above described, is a highly efficient one, and while the device described is the preferred embodiment of my present invention, I do not care to restrict myself to the exact details of construction, combination, and arrangement herein set forth, it being obvious that minor variations thereof not involving the exercise of invention may be made by any skilled mechanic, and such departures from what is herein described and claimed not involving invention, I consider as within the scope and terms of my claims.

85 I claim:

1. In a device of the character described, 100 two outside U-shaped bag frame members, an intermediate U-shaped bag frame member, and means for pivotally connecting the lower ends of said bag frame members, the outside bag frame members each comprising 105 a main body portion and end members extending therefrom formed from an unbroken flat piece of sheet metal, and a continuous reinforced upwardly and outwardly projecting flange extending around the in- 110

- ner edge of said body portion and the end members, and adapted to inclose said intermediate member when said outside frame members are in closed position, the intermediate frame member comprising an unbroken channeled body portion having end members extending therefrom, the intermediate frame member being adapted to underlie the abutting flanges extending along 10 the inner edges of the outside frame members and to lie within the space between the flanges extending from said outside frame members.
2. In a device of the character described, 15 two outside bag frame members, an intermediate bag frame member, and means for pivotally connecting the lower ends of said bag frame members, the outside bag frame members each comprising a channeled strip formed from an unbroken flat piece of sheet metal, and a continuous flange extending

around the inner edge of each of said members, said flange being formed by overlapping the metal of which said frame members are formed and adapted to inclose said 25 intermediate member when said outside frame members are in closed position, the intermediate member comprising a channeled strip formed from an unbroken flat piece of sheet metal, the intermediate frame 30 member being adapted to underlie the flanges extending along the inner edges of the outside frame members and to lie within the space between the flanges extending from said outside frame members.

35 This specification signed and witnessed this 23rd day of May, 1912.

FRANZ A. FULLER.
